US0D1071969S

(12) **United States Design Patent** (10) **Patent No.:** **US D1,071,969 S**
(45) **Date of Patent:** **** Apr. 22, 2025**

(54) **DISPLAY SCREEN WITH GRAPHICAL USER INTERFACE**

(71) Applicant: **Walmart Apollo, LLC**, Bentonville, AR (US)

(72) Inventors: **Benjamin R. Ellison**, San Francisco, CA (US); **Ravi Kumar Dalal**, Dallas, TX (US)

(73) Assignee: **Walmart Apollo, LLC**, Bentonville, AR (US)

(**) Term: **15 Years**

(21) Appl. No.: **29/971,033**

(22) Filed: **Oct. 31, 2024**

Related U.S. Application Data

(62) Division of application No. 29/772,546, filed on Mar. 2, 2021, now Pat. No. Des. 1,054,430.

(57) **CLAIM**

The ornamental design for a display screen with graphical user interface, as shown and described.

DESCRIPTION

The FIGURE is a front view of a display screen with graphical user interface showing the new design.

The outermost broken lines depict an electronic device and form no part of the claimed design. The broken line rectangle depicts a display screen and forms no part of the claimed design. The remaining broken lines depict portions of the graphical user interface and form no part of the claimed design.

1 Claim, 1 Drawing Sheet
